UNITED STATES PATENT OFFICE.

ALBERT STEFFIN, OF NEW BEDFORD, MASSACHUSETTS, ASSIGNOR TO THE PAIRPOINT CORPORATION, OF NEW BEDFORD, MASSACHUSETTS.

DESIGN FOR A COFFEE-POT.

SPECIFICATION forming part of Design No. 36,877, dated April 12, 1904.

Application filed February 10, 1904. Serial No. 193,017. Term of patent 7 years.

To all whom it may concern:

Be it known that I, ALBERT STEFFIN, a citizen of the United States, residing at New Bedford, in the county of Bristol and State of Massachusetts, have invented a new, original, and ornamental Design for a Coffee-Pot, of which the following is a specification, reference being had to the accompanying drawing, forming part thereof.

10 The accompanying drawing shows in perspective elevation a coffee-pot embodying my new design.

What I claim as new, and desire to secure by Letters Patent, is—15 The ornamental design for a coffee-pot, as shown.

ALBERT STEFFIN.
